UNITED STATES PATENT OFFICE.

PETER THOMAS HAYWARD AND WILLIAM PATRICK SANDERSON, OF COLLIE, WESTERN AUSTRALIA, AUSTRALIA.

STEAM-EXHAUST NOZZLE.

1,105,514.

Specification of Letters Patent.

Patented July 28, 1914.

Application filed July 28, 1913. Serial No. 781,625.

To all whom it may concern:

Be it known that we, PETER THOMAS HAYWARD and WILLIAM PATRICK SANDERSON, both subjects of the King of Great Britain, 5 and residing at Collie, Western Australia, Commonwealth of Australia, have invented certain new and useful Improvements in Steam-Exhaust Nozzles, of which the following is a specification.

- 10 This invention has been designed to provide an improved nozzle for use in connection with the now-existing steam exhaust pipes of locomotives, which nozzle, by reason of its form of construction, will reduce 15 the back or return steam pressure to a minimum with consequent gain in working efficiency and economy of fuel, the nozzle also acting, in some measure, as a spark extinguisher and arrester.
- 20 The nozzle consists of a circular, tapered or frusto-conical casing having an internal annular wall which depends to about half the depth of the outer casing. This wall is formed with steam exit ports and is encircled by a deflecting sleeve or ring that is 25 adapted to loosely move thereon in a vertical direction, for which purpose it is formed with slots and provided with stud bolts. The outer casing is adapted for operative 30 connection to the mouth of the exhaust pipe.

The invention will be clearly understood from the accompanying drawing, in which—

Figure 1 is an elevation showing the nozzle held in its working position over the exhaust pipe, the latter being shown in broken lines; Fig. 2 is a vertical section of the nozzle; Fig. 3 is a side elevation, partly in section, of the sleeve; and Fig. 4 is a horizontal section on line $x-x$ of Fig. 1.

- 40 In said drawing, a is the outer casing, of a tapered or frusto-conical form and having the internal annular wall b depending therefrom, as seen. This wall b is made with the exit or relief ports c for the escaping steam, 45 and is encircled by the deflecting sleeve or ring d which is slidable vertically thereon in either direction, and is supported in working position, as shown in Fig. 2, by means of stud bolts f . The said bolts are threaded 50 through shoulders g provided on casing a and project at their inner ends through vertical slots e formed in sleeve d and then

into holes formed therefor in the wall b . To give ease of vertical movement to the said sleeve, it is made with recesses or insets d^1 , 55 which afford relief and reduce frictional contact between said sleeve and the wall b . The outer casing is equipped with forked lugs j , whereby the nozzle as a whole may be secured by bolts m to the mouth of the 60 steam exhaust pipe n , the latter being represented in dotted lines in Fig. 1.

The purpose of the sleeve d is to deflect and divert around its side and over its top a certain portion of the escaping steam from 65 the pipe n , whence such steam passes downward between the sleeve and the wall b , rejoins the main body of steam, and escapes therewith, thus compressing or nozzleing the same as it passes up the funnel. The sleeve 70 has a limited vertical travel, owing to the provision of the slots e and bolts f , so that it is allowed to vibrate and thus prevent the passage from being steam choked. When said sleeve falls, it exposes the ports 75 c , such fall being caused by the back or return pressure of the steam in the funnel.

We claim:—

A steam exhaust nozzle for locomotives, comprising a hollow, frusto-conical casing 80 formed with a plurality of apertures; a vertical, annular wall arranged within the interior of said casing and having its upper end joined to the corresponding casing end; a deflecting sleeve loosely encircling said 85 wall for vertical movement relative thereto in either direction, and provided with a plurality of vertical slots corresponding in number to the apertures in the casing; and a plurality of inwardly projecting members 90 having their outer ends mounted in said apertures and their inner ends engaged with said wall, said members passing loosely through said slots to support said sleeve in place and limit its said movement. 95

In testimony whereof we have hereunto set our hands in presence of two subscribing witnesses.

PETER THOMAS HAYWARD.
WILLIAM PATRICK SANDERSON.
